US0D1078246S

(12) United States Design Patent (10) Patent No.: US D1,078,246 S
(45) Date of Patent: * Jun. 10, 2025

(54) SHOE

(71) Applicant: NIKE, Inc., Beaverton, OR (US)

(72) Inventor: Marie Odinot, Portland, OR (US)

(73) Assignee: NIKE, Inc., Beaverton, OR (US)

() Term: 15 Years

(21) Appl. No.: 29/922,532

(22) Filed: Dec. 22, 2023

(51) LOC (15) Cl. 02-04

(52) U.S. Cl.

USPC D2/947

(58) Field of Classification Search

USPC D2/896, 902, 903, 906-910, 916, 918, D2/919, 923-925, 947-949, 951-962, 977

CPC A43B 1/00; A43B 1/0063; A43B 1/023; A43B 1/028; A43B 1/10; A43B 1/12; A43B 1/14; A43B 3/00; A43B 3/0036; A43B 3/02; A43B 3/10; A43B 3/12; A43B 3/128; A43B 3/14; A43B 3/246; A43B 5/00; A43B 5/001; A43B 5/002; A43B 5/007; A43B 5/02; A43B 5/06; A43B 5/08; A43B 5/10; A43B 5/14; A43B 5/145; A43B 7/00; A43B 7/087; A43B 7/14; A43B 7/18; A43B 7/32; A43B 9/00; A43B 9/02; A43B 9/04; A43B 9/12; A43B 9/16; A43B 9/18; A43B 9/20; A43B 13/00; A43B 13/02; A43B 13/023; A43B 13/026; A43B 13/04; A43B 13/06; A43B 13/12; A43B 13/122; A43B 13/125; A43B 13/127; A43B 13/14; A43B 13/141; A43B 13/143; A43B 13/145; A43B 13/146; A43B 13/16; A43B 13/18; A43B 13/181; A43B 13/187; A43B 13/188; A43B 13/189; A43B 13/20; A43B 13/22; A43B 13/223; A43B 13/24; A43B 13/28; A43B 13/30; A43B 13/32; A43B 13/34; A43B 13/36; A43B 13/37

CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the shaded area define the bounds of the claimed design and form no part thereof. The broken lines depicting the remainder of the shoe form no part of the claimed design.

1 Claim, 3 Drawing Sheets
